UNITED STATES PATENT OFFICE

BRUNO LAURIS LAURSEN, OF DUNEDIN, FLORIDA, ASSIGNOR, BY MESNE ASSIGNMENTS, OF FORTY-EIGHT PER CENT TO CLEARWATER LUMBER COMPANY, INCORPORATED, OF CLEARWATER, FLORIDA, A CORPORATION OF FLORIDA

FOLDING FURNITURE

Application filed April 23, 1927. Serial No. 185,969.

This invention pertains to folding furniture, particularly tables and ironing boards.

It is an object of the invention to disclose a combined table and ironing board so arranged that either may be used without interference from the other.

Another object is to so arrange the above combination that it may be enclosed in a cabinet which, in turn, may be attached to a wall or installed in a wall or partition, even in a partition less than four inches thick.

Another object is to so arrange the combination that the units thereof will remain in either operative or non-operative position without use of fasteners of any kind.

Another object is to so arrange the units that the operator may move the units from operative to non-operative position, or vice versa, in a single continuous movement and with the use of only one hand.

Another object is to so design the device that there are no supports or other parts to occupy floor space around the cabinet or underneath the table or board under any condition of operation or non-operation.

Another object is to provide an arrangement in which the movable members are approximately balanced, thereby avoiding accidents due to the members falling on the operator.

Another object is to so design the furniture that the table top forms the front of the cabinet when the device is closed.

Another object is to be able, by changing only the table top, to adapt the front of the cabinet to harmonize with the surroundings in which it is to be placed.

Further and other objects and advantages will be hereinafter set forth in the accompanying specification and claims and shown in the drawings, which by way of illustration show what is now considered the preferred embodiment of the invention.

Fig. 1 is a front view of the cabinet with table and ironing board in closed, or inoperative, position.

Fig. 2 is a cross-section of Fig. 1, on the line 2—2 of Fig. 1.

Fig. 3 is a cross-section on the line 2—2

of Fig. 1 but with ironing board in operative, and table top in inoperative, positions.

Fig. 4 is a detail cross-section on the line 4—4 of Fig. 3.

Fig. 5 is a cross-section on the line 2—2 of Fig. 1 but with the table in operative position.

Fig. 6 is a detail cross-section on the line 6—6 of Fig. 5.

The arrangement may best be understood by reference to Fig. 5, which shows the device completely open and the rectangular table 10 in operative position, resting on top of the tapered ironing board 12, which is, in turn, supported by inclined brace member 14 secured at its lower end by hinge 16 to the bottom cross member 18 of the cabinet. The upper end of brace 14 is hinged to board 12 by the trunnion-like ends of cross bar 20 projecting through holes in blocks 22 (Fig. 4) attached to board 12 on its under side.

The cabinet end of board 12 has fastened to it a cross bar 24 having trunnion ends 26 engaging slots in the inner surfaces of the vertical side members 28 of the cabinet (Figs. 5 and 6). Each slot comprises a long vertical section 30 and a short horizontal section 32, as will be understood from Fig. 5.

It will be evident that the weight of board 12 will always tend to keep trunnions 26 in the outer ends of slots 32 whenever the device is in position for use, which means that no auxiliary fasteners are needed.

The table top 10, at its end toward the cabinet, is provided on its under side, near its edges, with blocks 34 bored horizontally to engage trunnions 26, as may best be seen in Fig. 6.

It will be evident from the above description that when the table is in operative position it rests on top of the ironing board, being pivotally engaged at its inner end by trunnions 26. For clarity of illustration top 10 and board 12 are shown in Fig. 5 with space between them, but in reality they are in contact. Near the middle of its length the table top is provided with a hinged joint, in the form of hinges 36.

Fig. 5 shows the arrangement when the

operator desires to use the table 10. If he wants to use the ironing board 12 he simply folds the table top 10 back out of the way as shown in Fig. 3, leaving the board 12 ready for use. The outer end of table 10 may be moved upwardly from the position shown in Figure 5, independently of the board 12 and without the hook member 44 engaging the outer end of the board; said hook member 10 on said upward movement of the outer end of the table 10 clearing the outer end of the board 12. Hinge 36 permits the table top to fold into the upper half of the cabinet, its weight being carried by trunnions 26. As its center of gravity is behind trunnions 26 it remains in this raised position without being fastened.

If it be desired to fold both table 10 and ironing board 12 into the cabinet, they are 20 first placed in the position shown in Fig. 5, then the operator pushes inwardly and downwardly on the outer free ends of table and board. The inward push moves trunnions 26 out of horizontal slot 32 into the 25 lower end of vertical slot 30 and the downward push swings table and board about bar 20 as a pivot until they are in the position shown in Figs. 1 and 2, in which it 30 will be seen that the table top 10 comprises the front exposed surface of the cabinet, surrounded by the frame composed of bottom member 18, side members 28 and top member 38. The cabinet may, if desired, be fitted with a back 40. The cabinet may be 35 attached to the surface of the wall or set into the wall, as desired. The top member 38 is grooved at its underside, Figures 2, 3 and 5, to receive the upper end of the table 10 when the device is fully closed.

40 The cabinet is opened and the table and board moved to operative position by using pull handle 42 to draw out the table top. When this is done the top bends at the hinge and the hook member 44 (Fig. 2) engages 45 i. e., moves upwardly into engagement with the end of board 12 so that further movement of the table will bring board 12 with it to the position shown in Fig. 5. This opening operation is accomplished in a single 50 continuous movement of table top and board outwardly and upwardly, pivoting about bar 20 in the direction opposite to the closing movement previously described.

55 While in closed position trunnions 26 in the upper end of slot 30 prevent the upper end of table and board from moving outwardly, therefore the parts remain in closed position automatically without use of fasteners until the midsection of the table top is 60 drawn outwardly by handle 42, whereupon hook 44 engaged board 12 and the parts open up as described.

65 It will be observed that the weight of both table and ironing board is nearly evenly divided on both sides of pivot 20, thereby

removing the possibility of injury to the operator by the members moving suddenly while being changed from one operative position to the other.

70 It is to be understood that the invention is not limited to the construction herein specifically illustrated but can be embodied in other forms without departure from its spirit.

75 I claim—

1. In a device of the class described, a cabinet having vertical side members with slots in the inner surfaces thereof, each slot comprising a long vertical section and a short horizontal section, an ironing board having at its cabinet end trunnions engaging said slots, a brace extending between and hinged to the lower portion of the cabinet and said board, a table top engaging said trunnions at its end toward the cabinet and having at an intermediate point of its length a hinged joint; said board brace and top being foldable within the cabinet while not in operative position, and said top being of a length and a width to close the front of the 90 cabinet when the top is in inoperative position.

2. In a device of the class described, a cabinet having vertical side members with slots in the inner surfaces thereof, each slot comprising a long vertical section and a short horizontal section, an ironing board having at its cabinet end trunnions engaging said slots, a brace extending between and hinged to the lower portion of the cabinet and said board, a table top engaging said trunnions at its end toward the cabinet and having at an intermediate point of its length a hinged joint; said board brace and top being foldable within the cabinet while not in operative position, and said top being of a length and a width to close the front of the cabinet when the top is in inoperative position, and a hook member on the top arranged to engage the board so that movement of the 100 top to operative position will bring with it the board.

105 In testimony whereof I hereto affix my signature.
